UNITED STATES PATENT OFFICE.

WILLIAM S. ELLIOTT, OF PITTSBURGH, PENNSYLVANIA.

CONTROL APPARATUS FOR STEAM-BOILERS, &c.

1,281,316.

Specification of Letters Patent. Patented Oct. 15, 1918.

Application filed November 27, 1914. Serial No. 874,186.

To all whom it may concern:

Be it known that I, WILLIAM S. ELLIOTT, a citizen of the United States, residing at Pittsburgh, in the county of Allegheny and State of Pennsylvania, have invented a new and useful Improvement in Control Apparatus for Steam-Boilers, &c.; of which the following is a full, clear, and exact description, reference being had to the accompanying drawings, forming part of this specification, in which—

Figure 1 is an elevation largely diagrammatic showing the application of my invention to a battery of four boilers;

Fig. 2 is a side elevation partly broken away showing the damper-actuating connections;

Fig. 3 is a view partly in side elevation and partly in vertical section of one of the regulators; and

Fig. 4 is a sectional view showing a regulator on a larger scale.

My invention has relation to steam boiler control, and is designed to provide controlling apparatus of simple, efficient and reliable character, whereby a group or battery of steam boilers may be automatically controlled in such a way that a substantially uniform steam pressure and a substantially constant efficiency may be maintained.

My invention also provides a regulator forming a part of the controlling apparatus, and which may also be used for a variety of other purposes.

The particular nature of my invention will be best understood by reference to the accompanying drawings, in which I have shown the preferred embodiment thereof and which will now be described, it being premised, however, that the invention is susceptible of various changes in the construction and arrangement of the parts, without departing from the spirit and scope of the invention as defined in the appended claims.

In these drawings, the letters A, B, C and D designate four steam boiler furnaces and boilers, to which my improved controlling apparatus is shown applied. For each boiler furnace, I provide a suitable motive device, such as the double-acting fluid-actuated cylinder 2. The piston rod 3 of each cylinder 2 is connected to some suitable device or devices for controlling the furnace of that particular boiler. In the drawings, I have shown this controlling device as con-

sisting of a stack damper 4, counterweighted at 5, and having a flexible connection 6, extending from pulleys 8 and leading to the piston rod 3. The furnace-controlling device may, however, be of various other characters. For instance, a connection may extend from the piston 3 to the ash pit door of the furnace, to a steam blower valve, to a fan engine valve, to the valve or controller which controls the operation of the furnace stokers, or in the case of a gas-fired furnace, to the valve which controls the supply of gas to the furnace. I have indicated at 9 in Fig. 2 an auxiliary connection, which may be led to any one or more of these devices, as may be desired. I also provide for each furnace and boiler a regulating device by means of which the supply of actuating fluid to the motor 2 of that furnace is controlled. Each of these regulating devices is shown as consisting of two diaphragms 10 and 11, the diaphragm 10 having its pressure surface forming a part of a chamber 12; and the diaphragm 11 having its surface forming a part of a chamber 13. The chambers 12 of the series of regulators have connections 14, leading to a pipe line 15, which is connected to the common steam pipe line or header E supplied by the boilers. The pressure chambers 13 of the several regulating devices have connections 16 with a pipe line 17, which leads to a source of substantially constant pressure, such as an air receiver 18, supplied by a pump or compressor 19.

The two diaphragms of each regulator are connected by a member 20, to which a lever 21 is pivoted at the point 22. To counterbalance the weight of the diaphragms and their connection 20, the arm 21^a on the lever 21 has a counterweight 23; and this arm is suspended from the frame 24 of the regulator by a link 25. The other arm of the lever 21 has a jointed connection 26 with the stem 27 of a pilot valve. This pilot valve consists of two piston portions 28 and 29, which are arranged to reciprocate in a casing or cylinder 30. This casing or cylinder has an inner lining sleeve 31, formed at its upper end portion with an exhaust opening 32, and with a series of smaller outlet ports 33. The lower end portion of the bushing is formed with a similar exhaust port 34, and a similar series of smaller outlet openings 35. The port 32 and openings 33 con-

nect the interior of the sleeve 31 with an outlet connection 36 from which a pipe 37 leads to the upper end of the cylinder of the hydraulic motor for that boiler. The 5 part 34 and openings 35 open into a connection 38, from which a pipe 39 leads into the lower end portion of the cylinder. The valve casing or cylinder is provided at the bottom with an exhaust connection 40, having 10 a passage 41 leading upwardly into a bowl-shaped chamber 42, at the upper part of the casing. This passage 41 is provided to carry off any water which exhausts above the valve portion 28, through the port 32, as 15 hereinafter described. Each pilot valve casing has a supply connection 30^a, opening into the sleeve 31, intermediate the two piston portions 28 and 29. The connections 30^a from the several regulators lead to a supply 20 pipe 30^b which, in turn, may lead to any suitable source of supply.

The numerals 43 and 44 designate two springs, which are connected to opposite sides of the pilot valve operating arm of 25 the lever 21. These springs are connected at their outer ends to adjustable bolts 45, mounted in the frame 24. In practice, these bolts are adjusted to a point where the springs 43 and 44 are about to be put under 30 tension. The purpose of these springs is to render the action of the regulator less sensitive and prevent excessive slight oscillations of the lever 21, such as would otherwise be caused by small variations in the 35 opposing pressures in the pressure chambers 12 and 13.

In practice, it is desirable that the several regulators of the several motors 2 shall act 40 successively upon the boilers; that is to say, that one of the boilers shall at first be cut out or in, and if this does not take care of the decreased or increased demand for steam, then a second boiler shall be cut out or in and so on throughout the battery or group. 45 In this manner, the boilers not affected remain at their maximum efficiency. The arrangement should also be such that the last boiler to be cut out or slowed down will be the first one to be again cut in or speeded up, since such boiler is in the best condition to be quickest restored to its maximum efficiency. To accomplish these objects, the pilot valve actuating arm of each lever 21 is provided with an adjustable counterweight 46, shown in Figs. 1 and 3. By 50 a proper adjustment of these counterweights, it will be readily seen that the regulator or boiler A may be made to operate under a less change in pressure in the steam line than the regulator or boiler B, and so on, through the series of regulators. The last regulator to operate in one direction, therefore, will, of course, be the first to operate 55 in the reverse direction under the reverse condition of pressure in the steam line.

The advantages of my invention will be readily apparent, since it provides a very simple and efficient system of boiler control which can be relied upon to accurately and automatically take care of widely varying 70 demands on a battery of boilers. For instance, in the case of a peak load coming more or less suddenly on or off the boilers, the apparatus will operate automatically to take care of the changes in conditions. The 75 two diaphragms of each regulator are normally balanced between constant pressure supplied by the pipe line 17 and the pressure of the steam pipe line supplied by the boilers. Any material change in the latter will 80 at once operate the motor 2 to shift the pilot valve to effect the proper operation of the boiler furnace control device.

It will be noted from Fig. 4 that the parts of the regulator are shown in their normal 85 balanced condition. Any increase in pressure in the chamber 12 will move the pilot valve downwardly until its portion 19 begins to uncover the series of openings 35, thereby admitting actuating fluid to the lower end 90 of the corresponding motor cylinder. At the same time, the downward movement of the valve portion 28 will uncover the exhaust opening 32 and permit the actuating fluid to flow out of the cylinder 2 and 95 through the passage 41 to the outlet 42. On the other hand, any material decrease of pressure in the chamber 12, effects a reverse movement of the pilot valve by which the exhaust port 34 is opened with a simultaneous successive opening of the ports 33.

It will be obvious that the regulating apparatus as shown in Fig. 4 can be used for a variety of other purposes, wherein it is desired to control a valve or other device.

Certain broad features of my invention not claimed herein are claimed in my co-pending application, Serial No. 867,162, filed October 17, 1914.

I claim:

1. The combination with a plurality of steam boilers and their furnaces, of a regulator for each furnace, a motive device for each regulator, a controller for each motive device, a normally open pressure connection 115 between each controller and a common pipe line supplied by the boilers, and means whereby different motive devices require different changes in the pressure in said pipe line to effect their operation, substantially 120 as described.

2. The combination with a plurality of steam boilers and their furnaces, of a regulator for each furnace, a motive device for each regulator, a controller for each motive 125 device, a normally open pressure connection between each controller and a common pipe line supplied by the boilers, and means whereby the number of such devices which will be operated by any change in the pres- 130

sure in said pipe line will depend upon the extent of such change, substantially as described.

3. The combination with a plurality of 5 steam boilers and their furnaces, of a regulator for each furnace, a motive device for each regulator, a controller for each motive device, a normally open pressure connection between each controller and a common pipe 10 line supplied by the boilers, and means whereby the different motive devices will operate in predetermined order upon change in the pressure in said common pipe, substantially as described.

15 4. The combination with a plurality of steam boilers and their furnaces, of a regulator for each furnace, a motive device for each regulator, a controller for each motive device, a normally open pressure connection 20 between each controller and a common pipe line supplied by the boilers, and means whereby the different motive devices will operate in predetermined order upon change in the pressure in said common pipe and 25 whereby the number of motive devices which will operate during any period of change in such pressure is dependent upon the extent of such change, substantially as described.

5. The combination with a plurality of 30 boilers and their furnaces, of a regulating device for each furnace, a motor for operating each regulating device, a controller for each motor, each controller having a pressure member having a pressure connection 35 at one side with a common pipe line supplied by said boilers, and a connection at the other side with a source of constant fluid pressure, the different controllers having means whereby they operate by different 40 changes of pressure in the common pipe line, substantially as described.

6. The combination with a plurality of boilers and their furnaces, of a regulating device for each furnace, a motor for operating 45 each regulating device, a controller for each motor, each controller having a pressure member having a pressure connection at one side with a common pipe line supplied by said boilers, and a connection at 50 the other side with a source of constant fluid pressure, the different controllers having means whereby they will operate in a definite predetermined order, substantially as described:

55 7. The combination with a plurality of boilers and their furnaces, of a regulating device for each furnace, a motor for operating each regulating device, a controller for each motor, each controller having a pressure 60 member having a pressure connection at one side with a common pipe line supplied by said boilers, and a connection at the other side with a source of constant fluid pressure, the different controllers having 65 means whereby they will operate in a

definite predetermined order, and whereby the number of controllers which will operate in any given period is dependent upon the extent of the changes in said period in the pressure in said pipe line, substantially as 70 described.

8. The combination with a plurality of boilers and their furnaces, of a regulating device for each furnace, a motor for operating such regulating device, a controller for 75 each motor, each controller having a pressure member having a pressure connection at one side with a common pipe line supplied by said boilers, and a connection at the other side with a source of constant fluid 80 pressure, the different controllers having means whereby they will operate in a definite predetermined order and in reverse order under opposite changes in pressure in said common pipe line, substantially as 85 described.

9. The combination with a plurality of boilers and their furnaces, of a regulating device for each furnace, a motor for operating each regulating device, a controller for 90 each motor, each controller having a pressure member having a pressure connection at one side with a common pipe line supplied by said boilers and a connection at the other side with a source of constant fluid 95 pressure, together with variable loading means for said pressure members whereby they may be made to operate in a predetermined order, substantially as described.

10. The combination with a plurality of 100 steam boilers and their furnaces, of a regulator for each furnace, a motive device for each regulator, a controller for each motive device, and a pressure connection between 105 each controller and a steam chamber common to the steam delivery of all the boilers, said regulators having means whereby they may either all be set to operate substantially simultaneously under a predetermined change in the conditions in said steam chamber, or to operate successively under different changing conditions in said chambers, 110 substantially as described.

11. The combination with a plurality of steam boilers and their furnaces, of a regulator for each furnace, a motive device for each regulator, a controller for each motive device, and a pressure connection between each controller and a steam chamber common to the steam delivery of all 120 the boilers, said regulators having means whereby they may either all be set to operate substantially simultaneously under a predetermined change in the conditions in said steam chamber, or to operate successively under different changing conditions in said chamber, 125 substantially as described.

12. A regulator comprising two connected diaphragm members, a lever operatively con- 130

4
nected to both said members, a shiftable weight on one arm of said lever, and a control device operatively connected with said lever, together with opposing springs each connected at one end to said lever, substantially as described.

13. A regulator comprising two connected diaphragm members, a lever operatively connected to both said members, a shiftable weight on one arm of said lever, and a control device operatively connected with said

lever, together with opposing springs each connected at one end to said lever, and another balancing weight on said lever, substantially as described.

15 In testimony whereof, I have hereunto set my hand.

WILLIAM S. ELLIOTT.
